(57) **CLAIM**

The ornamental design for a power tool as shown and described.

DESCRIPTION

FIG. 1 is an isometric view of a power tool.

FIG. 2 is another isometric view of the power tool of FIG. 1.

FIG. 3 is a top plan view of the power tool of FIG. 1.

FIG. 4 is a bottom plan view of the power tool of FIG. 1.

FIG. 5 is a front elevation view of the power tool of FIG. 1.

FIG. 6 is a rear elevation view of the power tool of FIG. 1.

FIG. 7 is a right side elevation view of the power tool of FIG. 1; and,

FIG. 8 is a left side elevation view of the power tool of FIG. 1.

Portions of FIGS. 1 through 8 are shown in evenly spaced broken lines illustrating portions of the article that form no part of the claimed design. The dash-dot-dash broken lines in the drawings illustrate the boundaries of the claimed design, which form no part thereof.

1 Claim, 8 Drawing Sheets
